JOSEPH E. BROWNE, OF MOUNTAIN LAKES, NEW JERSEY, ASSIGNOR TO SILVERBERG
IMPORT COMPANY, INCORPORATED, A CORPORATION OF NEW YORK.

HAIRPIN.

1,360,494.

Specification of Letters Patent. Patented Nov. 30, 1920.

Application filed March 13, 1918, Serial No. 222,067. Renewed August 12, 1920. Serial No. 403,139.

To all whom it may concern:

Be it known that I, JOSEPH E. BROWNE, a citizen of the United States of America, and resident of Mountain Lakes, in the county of Morris and State of New Jersey, have invented 5 certain new and useful Improvements in Hairpins, of which the following is a specification.

My invention relates to an improvement in 10 hair pins.

I have illustrated said invention in the accompanying drawing referring to like parts by like numerals.

Figure 1 is a front elevation, and Fig. 2 a 15 side elevation.

The hair pin is formed from two sections of spring wire or it may be made of any other material that is adapted to take and retain the form indicated and have the quality 20 of elasticity in the sense of a spring, when a resistant object as a mass of hair is interposed between the arms. I will however describe it as made of wire.

Two sections of wire as 1 and 2 are twisted 25 together as at 3 and bent as indicated in the drawing, thus forming two bifurcated members united at 3. Said members are substantially in one and the same plane and are intended to coöperate when the hair pin is introduced into a mass of hair, by reason of 30 the fact that a portion of said mass passes between the arms first of the longer member and then between the arms of the shorter of said members. I have indicated the two bifurcated members as $a-a$ and $b-b$.

I am aware that hair pins of this general type, that is, comprising two bifurcated members one included within the other, is known in the art. I therefore do not intend 40 to claim such structures broadly, but only in a limited sense to cover the particular arrangement of curvatures for each bifurcated member in its relation to the other bifurcated member. For example, in the structure as 45 illustrated in the member $a-a$, I provide two bulging sections as $a'-a'$, a^2-a^2 with a depressed section between them as a^3-a^3 .

The ends or termini are also formed to diverge as indicated. So in forming the smaller 50 bifurcated member I provide a bulged section as at $b'-b'$ and a depressed section as at b^2-b^2 and the termini of section b are turned outwardly, that is diverge, as indicated at b^3-b^3 .

In operation the hair when the pin is introduced passes between the arms $a-a$, thence between the arms b^3-b^3 and also is forced between the outer wall of the inner member $b-b$ and the inner walls of the outer member $a-a$. When all of this space is filled 60 with strands of hair, the two members $a-a$ and $b-b$ coöperate to grip the hair between them, and the ropes or masses of hair which are thus held are restrained from slipping out, because of the irregular form of the two 65 bifurcated members, that is to say, a portion of the hair is held within the arms $b-b$ and within the bulged section a^2-a^2 and $a'-a'$ and prevented from slipping out by the pressure exerted between said members a and b , 70 for it will be understood that when the hair pin is forced into the hair a great mass of hair is forced between the arms of said members by reason of their divergent termini and they are of necessity forced to expand, the 75 spring metal or material of which they are formed permitting a certain yielding incident to said operation. Hence the mass of hair is subject to said spring or elastic pressure, and it is confined within said bulging 80 sections and between the inner and outer bifurcated members.

What I claim is:

A hair pin formed from two sections of wire twisted together adjacent one end of 85 each to form a union between them and to form two bifurcated members one longer than the other the shorter inclosed within the longer and both in substantially the same plane, the longer member having two bulging 90 sections and two depressed sections with diverging termini, while the shorter member has one bulging section and one depressed section with diverging termini, the shorter member situated adjacent the head of the 95 pin, with its curvatures corresponding substantially with the curvatures of the longer member adjacent thereto, its divergent termini expanding into a bulged section.

Signed by me at New York city, N. Y., this 100
11th day of March, 1918.

JOSEPH E. BROWNE.
